ANTON F. WOLFF, OF GENESEE, IDAHO

TOY AIRPLANE

Application filed July 7, 1931. Serial No. 549,250.

This invention relates to toys of the aerial type and of the character supported by a stand and around which the toy aircrafts are adapted to travel and also ascend and descend during their travel, and has for the primary object, the provision of an improved operating medium for imparting movements to the toy aircrafts without the danger of said operating medium becoming tangled with the stand and which includes a novel type of weight adapted to automatically disconnect itself from the device when reaching its lowermost position so that the toy aircrafts may continue their travel by gravitation having first been elevated by the descent of the weight.

With this and other objects in view, this invention consists in certain novel features of construction, combination and arrangement of parts to be hereinafter more fully described and claimed.

For a complete understanding of my invention, reference is to be had to the following description and accompanying drawings, in which—

Figure 1 is a side elevation illustrating a toy constructed in accordance with my invention.

Figure 2 is a fragmentary vertical sectional view illustrating the same.

Figure 3 is a fragmentary side elevation illustrating the weight in the act of disconnecting itself from the operating medium.

Figure 4 is a fragmentary perspective view of the weight and a portion of the operating medium.

Referring in detail to the drawings, the numeral 1 indicates a pedestal carrying a vertically disposed shaft or stand 2 to which is secured at the upper end thereof a shaft 3 provided with a squared portion 4 on which is secured a drum 5. A similar drum 6 is journalled on the shaft 3 below the drum 5 and the lower end bears against the upper end of the stand 2. A substantially arcuate shaped arm 7 is provided with the bearing opening intermediate its ends to receive and is non-rotatably secured to the upper end of the stand 2. The ends of the arm 7 are bifurcated and have journalled therebetween

grooved pulleys 8 over which are trained cables or flexible elements 9. The elements 9 are wound upon the drum 6 and have their free ends connected by a weight bar 10 provided with a laterally disposed offset portion 11 adapted to partially receive the stand 2. A weight 12 consisting of elements 13 relatively spaced and connected by an arcuate shaped portion 14 are detachably secured to the bar 10 by hooks 15.

An arm 16 is journalled on the shaft 3 intermediate the ends thereof and is secured to the upper end of the drum 6 by bolts or like fasteners 17, the ends of the arm 16 having journalled thereto grooved pulleys 18 over which are trained cables or flexible elements 19. The elements 19 are wound upon the drum 5 with their free ends attached to toy aircrafts 20.

In operation, when the toy aircrafts 20 are in their lowermost position the weight 12 is manually applied to the bar 10 which is then in its uppermost position and due to the influence of the weight, the bar 10 moves toward the pedestal 1 imparting rotation to the drum 6 which rotates the arm 16 and winds the elements 19 about the drum 5 imparting to the toy aircrafts a movement in a circular path and in an upward direction. As the bevelled ends of the weight 12 strike the surface of the pedestal 1, the weight rocks and disengages the hooks 15 from the bar 10. The weight of the toy aircrafts is then sufficient to cause them to gravitate and this movement causes a rotation of the arm 16 in a reverse direction unwinding the elements 19 from the drum 5 and winding the elements 9 onto the drum 6 so that to repeat the operation of the device, the weight 12 is again manually applied to the bar 10, thus it will be seen that the toy aircrafts both travel in a circular path and descend and ascend. During the movement of the bar 10 upwardly or downwardly relative to the stand 2, it is prevented from becoming tangled therewith due to the arcuate shaped portion 11 engaging one side of the stand while the arcuate shaped portion 14 of the weight 12 engages the opposite side and also due to the non-rotation of the arm 7 the possibility of the elements 9

becoming tangled in their movements is entirely obviated either with the stand or with the toy aircrafts during their rotation either when ascending or descending.

While I have shown and described the preferred embodiment of my invention, it will be understood that minor changes in construction, combination and arrangement of parts may be made without departing from the spirit and scope of my invention, as 10 claimed.

Having thus described my invention, what I claim is:

1. A toy comprising a vertical stand, a shaft fixed to said stand and disposed vertically, 15 a rotatable drum on said shaft, a fixed drum on said shaft, an arm journalled on the shaft and secured to the rotatable drum, a second arm fixed to the stand, flexible elements wound on the fixed drum and trained over 20 the ends of the first arm and attached to toy aircrafts, a second flexible element wound on the rotatable drum and trained over the ends of the second arm, a bar connecting the free 25 ends of the second named flexible element and adapted to have sliding relation to the stand, and a self removable weight attached to the bar and adapted to automatically disconnect itself from said bar when engaged with the base of the stand.

2. A toy comprising a vertical stand, an arm fixed to the stand, a shaft fixed to the stand, rotating and non-rotating drums carried by said shaft, a second arm journalled on the shaft and secured to the rotating drum, 35 pulleys at the end of the arms, a flexible element wound on the fixed drum and passed over said pulleys of the second named arm and having its ends connected to toys, a second flexible element wound on the rotatable drum and passed over the pulleys of the first arm, a bar connected to the ends of the last named flexible element and having a curved portion disposed at one side of the stand, 40 a weight having an arcuate shaped portion disposed at the opposite side of the stand over the bar and detachably connected to said bar and having rounded shaped portions adapted when engaging the base of the stand to automatically disconnect the weight from the bar.

3. A toy comprising a base, a stand carried by said base, a shaft fixed to the stand, an arm fixed to the stand, rotatable and non-rotatable drums carried by the shaft, a second arm journalled on the shaft and secured to the rotatable drum, a flexible element wound on said fixed drum and trained over the ends of the second named arm and having 45 its ends connected to toy aircrafts, a second flexible element wound on the rotatable drum and trained over the ends of the first named arm, a bar connected to the ends of the last named flexible element and having a curved portion engaging one side of the

stand, a pair of weights connected by an arcuate shaped portion disposed at the opposite side of the stand from the bar, hooks carried by said weights and engaging the bar to detachably connect said weights to the bar, 70 said weights having curved faces adapted to cause the weights to tilt when in engagement with the base for disconnecting the hooks from the bar.

In testimony whereof I affix my signature. 75
ANTON F. WOLFF.
